CLAIM

The ornamental design for a batting practice device, as shown and described.

DESCRIPTION

FIG. 1 is a front view of a batting practice device showing my new design;

FIG. 2 is a left side view thereof;

FIG. 3 is a right side view thereof;

FIG. 4 is a top view thereof; and,

FIG. 5 is a bottom view thereof.

The broken line showing in FIG. 1 is for illustrative purposes only and forms no part of the claimed design.
